UNITED STATES PATENT OFFICE.

BEN JEDLITSCHKA, OF LOS ANGELES, CALIFORNIA.

GASOLINE METER FOR AUTOMOBILES, ETC.

Application filed November 16, 1920. Serial No. 424,403.

To all whom it may concern:

Be it known that I, BEN JEDLITSCHKA, a citizen of the United States, residing at Los Angeles, in the county of Los Angeles and 5 State of California, have invented new and useful Improvements in Gasoline Meters for Automobiles, Etc., of which the following is a specification.

It is the object of this invention to provide a meter particularly adapted for use in connection with the fuel supply for a motor vehicle and the like.

The invention will be readily understood from the following description of the accompanying drawings, in which:

Figure 1 is a longitudinal section through the meter.

Fig. 2 is a transverse section through the meter showing the top of the casing removed.

Fig. 3 is a detail section on the line 3—3 of Figure 1.

The meter is housed within a casing 1 divided by the vertical partition 2 into a 25 reservoir 3, and a pump cylinder 4 having a transverse partition 5 at its lower end spaced from the base of the casing so as to form a float chamber 6.

A transverse shaft 7 is journaled in the 30 upper part of reservoir 3 and extends into the pump cylinder where it is provided with a crank throw 8 connected to a pump rod 9 arranged to reciprocate pump head 10 within the pump cylinder 4. A gear 11 is loosely journaled upon shaft 7 within reservoir 3, and said gear is rotated by a worm 12 which is mounted upon a shaft 13. This shaft is constantly rotated from any suitable moving part of the engine upon 40 which the meter is employed. The shaft 13 and gear 11 constitute a continuous power. A sleeve 14 is fixed for rotation with shaft 7 and is axially movable along the same. Gear 11 and sleeve 14 are provided with co- 45 operating clutch members 15—16, which when the sleeve is shifted to cause engagement of the clutch will provide for the rotation of shaft 7 from the shaft 13.

The upper portion of partition 2 is provided with an opening 17 causing communication between the portion of pump cylinder 4 which is above the pump head, and the reservoir 3. The reciprocation of the pump head will draw fluid into the 55 pump cylinder through a port 18 in partition 5 which is normally closed by a check

valve 19. The pump head is provided with a valve 20 through which the fluid will pass when the pump is actuated, and the fluid thus pumped through the pump head is discharged through opening 17 to the reservoir 3. It will be noted that the construction as thus described provides a measuring pump wherein each reciprocation of the pump will discharge a predetermined amount of fluid 65 to the reservoir.

The reciprocation of the pump actuates suitable registering mechanism which is shown at 21 as provided with a total register 22 and a trip register 23. The register is 70 actuated in usual manner by a shaft 24 which is provided with engageable means such as a disc head 25 having the axially projecting circumferential pins 26. Engaging means such as a pin 27 upon the end of pump rod 75 9, which is connected to crank throw 8, is adapted to engage pins 26 so that at each reciprocation of the pump rod 6, the shaft of the registering mechanism will be turned. By this arrangement the amount of fluid 80 pumped to reservoir 3 will be accurately registered.

A port 18 through which fluid is drawn from the float chamber 6 to the pump cylinder is preferably arranged in a conduit depending toward the bottom of the float chamber from partition 5. A fluid intake 28 is provided in the float chamber, and is adapted to be closed by a needle valve 29 fixed upon a rock arm 30 which is actuated 85 by a float 31 within the float chamber so as to open the needle valve when the fluid level within the float chamber is lowered, and to close the needle valve when the float chamber has been filled. The fluid inlet 28 may 90 be provided with a suitable nipple 32 to which is connected a conduit leading from the fluid supply.

The reservoir 3 is provided with a discharge port 33 extending through a suitable 100 nipple 34 to which is connected a conduit leading to the carburetor of the engine upon which the meter is employed. The port 33 is provided with a two-way valve 35 so arranged that the fluid in reservoir 3 may be 105 discharged through port 33, or when the valve is turned to its second position the fluid in float chamber 6 will be discharged directly through port 33 by way of a bypass 36 extending from float chamber 6 to 110 the two-way valve.

Sleeve 14 is actuated to provide the driv-

ing connection for shaft 7 when the fluid pumped into reservoir 3 has reached a low level. For this purpose a float 37 is received in the reservoir and is slidable upon a guide rod 38. A rod 39 is connected to the float and is preferably also guided by rod 38. A bell crank lever 40 is pivoted to the casing 1 with one arm 41 thereof pivoted to rod 39, and the other arm 42 received in a groove 43 of the sleeve 14, the parts being so arranged that when the bell crank lever is swung upon its pivot through the rise and fall of float 37, sleeve 14 will be moved back and forth to engage and disengage the clutch 15-16.

When the meter is in use, valve 35 is turned to close by-pass 36 and cause the fluid in reservoir 3 to discharge through port 33. Fuel is supplied to float chamber 6 from the fuel tank, and when the fuel pumped to reservoir 3 has reached a low level, clutch 15-16 is engaged to actuate the measuring pump and thereby supply fuel to the reservoir. The amount of fuel thus supplied will be registered upon the registering mechanism, and as a consequence the device forms an accurate meter for the fuel used by the engine with which the meter is employed.

When it is desired to supply fuel to the carburetor of the engine without causing the meter to function, the valve 35 is turned so that the fuel is discharged directly from the float chamber through by-pass 36 to the port

33, and as a consequence the measuring mechanism will become inoperative.

Various changes may be made without departing from the spirit of the invention as claimed.

What is claimed is:

1. In an automatic, fuel supply and measuring device, a casing divided by a vertical wall into a reservoir and a pump chamber, pump actuating means in said reservoir, a valved piston in said pump chamber, a valved bottom in the pump chamber, and means for starting said pump actuating means whenever the liquid in said reservoir falls below a predetermined level, the dividing wall having a port for passage of fluid lifted by the piston, into the reservoir.

2. In an automatic, fuel supply and measuring device, a casing divided by a vertical wall into a reservoir and a pump chamber, a valved piston in said chamber, a valved bottom in the pump chamber, the dividing wall having a port for passage of fluid lifted by the piston, into the reservoir, a crank shaft enclosed in the casing and attached to the piston, means constantly running on the crank shaft, and means for automatically connecting said shaft and said means to intermittently replenish the reservoir supply.

In testimony whereof I have signed my name to this specification.

BEN JEDLITSCHKA.
